UNITED STATES PATENT OFFICE.

BENJAMIN F. DE KLYN, OF NEW YORK, N. Y.

DESIGN FOR A CANDY-MOLD SECTION.

SPECIFICATION forming part of Design No. 34,823, dated July 23, 1901.

Application filed June 6, 1901. Serial No. 63,469. Term of patent 14 years.

To all whom it may concern:

Be it known that I, BENJAMIN F. DE KLYN, a citizen of the United States, and a resident of the city of New York, borough of Manhattan, in the county and State of New York, have invented and produced a new and original Design for a Candy - Mold Section, of which the following is a full, clear, and exact description.

Reference is to be had to the accompanying drawings, forming a part of this specification, in which—

Figure 1 is an interior view of a candy-mold section, showing my design; and Fig. 2 is a cross-section on the line $x-x$ of Fig. 1.

The leading feature of my design for a candy-mold section consists in the elongated concave body of the general outline of a peanut and having a plurality of raised portions of irregular outline at the inner or concaved side.

Referring particularly to the drawings, the concaved mold-section has outwardly-curved ends 1 2, the outward curves 3 4 and inward curves 5 6 at one side, and the outward curves 25 7 8 and inward curves 9 10 at the opposite side, the curves 6 and 10 being near the ends, and within the body are the raised irregular surfaces.

Having thus described my invention, I 30 claim as new, and desire to secure by Letters Patent—

The design for a candy-mold section, as herein shown and described.

In testimony whereof I have signed my 35 name to this specification in the presence of two subscribing witnesses.

BENJAMIN F. DE KLYN.

Witnesses:

LOUIS M. FULTON,
JULIUS SCHÜLLINGER.
